UNITED STATES PATENT OFFICE.

GEORGE T. RONK, OF CEDAR RAPIDS, IOWA, ASSIGNOR TO SPEEDER MACHINERY CORPORATION, OF CEDAR RAPIDS, IOWA, A CORPORATION OF IOWA.

DITCHER CARRIER.

Application filed July 25, 1927. Serial No. 208,401.

This invention relates to improvements in ditcher mechanism of that type which is designed to be used in railroad work.

The object of my invention is to provide a ditcher mechanism of simple, durable and inexpensive construction, and which is adapted to be operated over the ordinary railway track, and having in connection therewith a series of dump cars which are so located that the ditcher may be operated while on the railway track and to empty the material in the dump cars, the dump cars and ditcher being designed to be operated over the track in a unit by power derived from the excavator operating mechanism, and including means whereby the ditcher advancing mechanism may be swung out of operation while the ditcher is being operated.

A further object is to provide a railway car for receiving a ditching machine of the tractor type, said car being so arranged that the maximum height of the ditcher is such as to permit the ditcher to be conveyed under standard bridges and trolley lines, said car including means whereby the ditcher may be easily and quickly moved to and from position thereon, and including means whereby the ditcher carrier may be propelled from the same power used to advance the ditcher.

30 A further object is to provide means for operatively connecting the power of the ditcher with the mechanism for propelling the railway car over its track.

A further object is to provide improved means for loading and unloading the ditcher from the ditcher carrier or car.

40 My invention consists in the construction, arrangement and combination of the various parts of the device, whereby the objects contemplated are attained, as hereinafter more fully set forth, pointed out in my claims, and illustrated in the accompanying drawings, in which:

45 Figure 1 is a side elevation of my improved mechanism.

Figure 2 is a detail sectional view on the line 2-2 of Figure 1, a portion of the car platform together with the traction device of the ditcher being broken away.

50 Figure 3 is a detail sectional view taken on the line 3-3 of Figure 2.

Figure 4 is a detail view of one of the universal joints of the power transmission device.

My improved mechanism comprises what I

shall term a ditcher carrier 10 comprising a 55 pair of railway trucks 11 and 12 designed to operate on the standard railway track 13. Each of the trucks 11 and 12 is designed to support a platform 14. The inner edge of each of the platforms 14 is provided with a 60 downwardly extending portion 15 designed to support a platform 16 supported a slight distance above the railway 13. The platform 16 is of the same width as the platforms 14. Each of the side edges of the platform 16 is 65 provided with a pair of hinged loading planks or platforms 17, which are adapted to swing from a vertical position to an inclined position below the top surface of the platform 16 in the manner clearly illustrated in Figure 3. Said planks are detachably supported to the platform 16 by means of hooks 18 supported on pivots 19, so that the planks may be removed if so desired, or they may be swung to the position shown by dotted lines in Figure 3.

One of the axles 20 of the truck 11 is provided with a worm gear 21 operating in a housing 22 and driven through a worm 23 mounted on a shaft 24, which has its inner 80 end extending to the frame member 15 and provided with one member of a universal joint 25. Supported adjacent to each end of the ditcher carrier 10 is a dump car 26 of ordinary construction.

85 The platform 16 is designed to receive and support a ditching machine 27 having the ordinary dipper 28 supported by means of a dipper boom 29 and the dipper stick 30, said boom 29 being supported by a cable 31 and 90 the dipper by means of a cable 32. These parts are of the ordinary construction.

The boom 29 is supported on a platform 33 pivoted to the ditcher truck 34, which is provided with the ordinary crawler type treads 95 35 of a length slightly less than the width of the platform 16. The said treads are designed to be supported on the platform 16 in a transverse manner, as clearly illustrated in the drawings. The spacing between the 100 loading planks 17 is the same as the spacing between the treads 35 so that when the planks are placed in their lowered position, the tractor may be moved transversely of the carrier 10, and operated on said planks to cause the 105 ditcher to be loaded or unloaded. The treads 35 are operated by means of a shaft 36 relatively mounted in the truck 34. Said shaft

has at each end sprockets 37 for operating the sprocket chains 38, which in turn operate sprockets 39 on the shafts 40, which carry the driving sprockets 41 of the said treads. The shaft 36 is driven with the bevel gear 42 rotatively mounted on the said shaft and driven through a bevel gear 43 mounted on the lower end of a vertical shaft 44. A clutch 45 is feathered to the shaft 36 to throw the gear 42 into and out of operative relation with the shaft 36. A bevel gear 46 is also rotatively mounted on the shaft 36 driven through the bevel gear 43 and provided with a hub 47. A gear 48 is mounted on the hub 47 and in mesh with a gear 49 mounted on a stub shaft 50. The inner end of the shaft 50 has a universal joint 51 carrying a square shaft 52 telescopically mounted in a sleeve 53 carried by the universal joint 25.

20 By this arrangement it will be seen that power for advancing the carrier 10 may be derived from the shaft 44, which is also employed for operating the tread members 35.

In Figure 4, I have shown in detail one of the universal joints, both of which are alike, in which a detachable pin 54 is employed for mounting the spider within one of the bifurcated members, so that if the pin 54 is withdrawn, then the spider together with the other bifurcated member of the universal joint, as well as the shafts 52 and 53, may be entirely removed, if so desired, by pulling both of the pins 54. Or, if it is desired to throw the carrier 10 out of operative relation with the driving shaft 44, only one of the pins 54 need to be removed.

Other mechanism might be provided for operatively connecting the shafts 24 and 50. In any event the universal joints and the telescopic shaft should be included, as it will readily be seen that some difficulty would otherwise arise in properly alining the shaft 50 with the shaft 24.

The distance between the dump cars 26 is such that the dipper 28 may be swung into dumping position above either of said cars. The said dipper 28 is adapted to be supported on one of the platforms 14 when not in use, in the manner illustrated by dotted lines in Figure 1, which provides means for steady- 50 ing the excavator platform 33. Other anchoring devices would have to be provided, such as blocking the treads 35 and bracing the platform 33 against rotation on its vertical shaft if the carrier were used in rapid transit.

By this arrangement it will be seen that I have provided a railway dumper mechanism which is capable of very flexible operation, 60 the dumper being rapidly transferred from one job to another by connecting the dumping cars 26 in series with the ordinary freight train, or the said dumping cars 26 and the carrier may be advanced independently over 65 the tracks by their own power, as above de-

scribed. The dipper 28 may be operated if so desired while the machine rests on the platform, or the dumper may be easily and quickly removed and operated at any desired point along the side of the track, and 70 used for dumping material in said cars, in which case independent advancing mechanism might be placed on one of the platforms 14 and power transmitted to the worm gear 21 in place of the shaft 24, in which case the 75 carrier 10 and the dumper machine may be operated independently.

The railway carrier car, as well as the dumping cars, may be equipped with any of the standard brake systems.

I claim as my invention:

1. In combination, a railway dumper carrier car, comprising a pair of trucks and a platform supported thereon, the central portion of said platform being lowered between said trucks and adapted to carry and support a dumper machine of the boom and bucket type, and a dumping car adjacent to each end of said dumper carrier car, the cars being so arranged and the carrier car of such length that the bucket of the dumper machine may be emptied in either of said dumping cars.

2. In combination, a railway dumper carrier car, comprising a pair of trucks and a platform supported thereon, the central portion of said platform being lowered between said trucks and adapted to carry and support a portable dumper machine of the boom and bucket type, a dumping car adjacent to each end of said dumper carrier car, the cars being so arranged and the carrier car of such length that the bucket of the dumper machine may be emptied in either of said dumping cars, and means carried by said lowered platform 100 for attaching dumper machine loading and unloading planks.

3. In combination, a railway dumper carrier car, comprising a pair of trucks and a platform supported thereon, the central portion of said platform being lowered between said trucks and adapted to carry and support a portable dumper machine of the boom and bucket type, a dumping car adjacent to each end of said dumper carrier car, the cars being so arranged and the carrier car of such length that the bucket of the dumper machine may be emptied in either of said dumping cars, and loading and unloading planks pivotally mounted to one side of said lowered platform to project laterally and horizontally therefrom.

4. A railway dumper machine carrier car comprising a pair of car trucks spaced apart, a platform supported by and connecting said trucks, the central portion of said platform being lowered between said trucks to a point slightly above the rails on which the trucks are supported, and loading and unloading planks pivoted to one of the side edges of said 130

lowered platform, said planks being designed to swing from a vertical to a horizontal position.

5. In combination, a railway ditching machine carrier car comprising a pair of trucks and a platform supported thereby, the central portion of said platform being lowered, a tractor type ditching machine carried by said platform, a power device carried by said ditching machine, means actuated from said power device for advancing the ditching machine over the ground surface, and means actuated from said power device for propelling said railway car.
15. 6. In combination, a railway ditching machine carrier car comprising a pair of trucks and a platform supported thereby, the central portion of said platform being lowered, a tractor type ditching machine carried by said platform, a power device carried by said ditching machine, means actuated from said power device for advancing the ditching machine over the ground surface, means actuated from said power device for propelling said railway car, and means for throwing either said ditcher advancing means or said car advancing means into and out of operation with said power device.

7. In combination, a railway ditching machine carrier car comprising a pair of trucks and a platform supported thereby, the central portion of said platform being lowered, a tractor type ditching machine carried by said platform, a power device carried by said ditching machine, means actuated from said power device for advancing the ditching machine over the ground surface, means actuated from said power device for propelling

said railway car, means for throwing either said ditcher advancing means or said car advancing means into and out of operation with said power device, and a dump car connected to one end of said carrier car to receive material delivered by said ditching machine.

8. In combination, a railway ditcher carrier car, comprising a pair of trucks and a platform supported thereon, the central portion of said platform being lowered between said trucks and adapted to carry and support a portable ditching machine of the boom and bucket type, a dumping car adjacent to each end of said ditcher carrier car, the cars being so arranged and the carrier car of such length that the bucket of the ditching machine may be emptied in either of said dumping cars, loading and unloading planks pivotally mounted to one side of said lowered platform to project laterally and horizontally therefrom, and means for advancing said carrier car on its supporting rails.

9. In combination, a railway ditcher carrier car, comprising a pair of trucks and a platform supported thereon, the central portion of said platform being lowered between said trucks and adapted to carry and support a ditching machine of the boom and bucket type, a dumping car adjacent to each end of said ditcher carrier car, the cars being so arranged and the carrier car of such length that the bucket of the ditching machine may be emptied in either of said dumping cars, and means for advancing said carrier car on its supporting rails.

Des Moines, Iowa, July 20, 1927.
